(57) **CLAIM**

The ornamental design for a milling machine for use in a dental laboratory system, as shown and described.

DESCRIPTION

This application is related to application Serial No. 29/233,726, titled digitizer machine for use in a dental laboratory system filed Jul. 8, 2005; and This application also is related to application Serial No. 29/233,791, titled dental laboratory system workstation filed Jul. 8, 2005.

The article in which the design is embodied is a milling machine for fabricating dental restorations and is intended for use in a dental laboratory system.

FIG. 1 is a perspective view of the milling machine as viewed from a left side;

FIG. 2 is a top plan view of the milling machine of FIG. 1; FIG. 3 is a perspective view of the milling machine as viewed from a right side;

FIG. 4 is an elevation view of the milling machine as viewed from the left side;

FIG. 5 is a front view of the milling machine;

FIG. 6 is an elevation view of the milling machine as viewed from the right side;

FIG. 7 is a back view of the milling machine; and,

FIG. 8 is a bottom view of the milling machine.
